E. W. BLACKWOOD

INHALER

Filed Feb. 9, 1921

INVENTOR
Edward W. BLACKWOOD
By Edward E. Longman
ATTY.

UNITED STATES PATENT OFFICE.

EDWARD W. BLACKWOOD, OF ST. LOUIS, MISSOURI.

INHALER.

Application filed February 9, 1921. Serial No. 443,697.

To all whom it may concern:

Be it known that I, EDWARD W. BLACKWOOD, a citizen of the United States, and resident of the city of St. Louis, State of Missouri, have invented certain new and useful Improvements in Inhalers, of which the following is a specification containing a full, clear, and exact description, reference being had to the accompanying drawings, forming a part hereof.

My invention relates to improvements in inhalers, and has for its primary object the construction of an inhaler for administering fumes to the patient for the treatment of catarrh, asthma and all bronchial and pulmonary troubles.

In the drawings—

Fig. 1 is a side elevation of my inhaler, supplied with medicine and ready for use; Fig. 2 is a vertical, longitudinal section taken on the line 2—2 of Fig. 3; and

Fig. 3 is a top plan view of my improvement.

Referring to the drawings:

4 indicates a container made of any suitable material, preferably of glass. The container is provided with an enlarged lower portion 5 and a narrow neck portion 6. Mounted in the top of the neck is a closure 7, provided with a flange 8, adapted to rest on the top edge of the neck portion 6.

Formed in the closure 7 is an opening, and seated in said opening and projecting through the closure 7 is a hollow closure 9. The hollow closure 9 is provided with a flange 10 which rests on the top edge of the closure 7. The closure 7 is also provided with another opening 11, through which is inserted a tube 12 which extends down and in close proximity to the bottom of the container 4. This tube 4 is provided with a goose-neck 13, the open end of which is located in the hollow closure 9.

Located in the hollow closure 9 and surrounding the open end of the goose-neck 13 is a body of medicated cotton or analogous material, 14.

15 indicates a mouth-piece having a flattened end 16 for insertion in the mouth of the person being treated, and the opposite end extends through a suitable opening formed in the closure 7.

In the practical operation of my improvement, the container 4 is filled with the desired medicinal preparation, as indicated in Fig. 2, which is in the form of a solution. The closure 7 is then inserted in the neck of the container and the tube 12 projects down into the medicinal preparation. The mouthpiece 15 is then inserted into a suitable opening formed in the closure 7, and then, by inserting into the mouth the flattened portion 16 and inhaling, the air will be drawn down through the tube 12 and the medicinal preparation and the fumes will be administered.

The hollow closure 9 directs the air down through the tube 12 and through the medicinal preparation. The body of medicated cotton or analogous material 14 will strain the impurities out of the air before its passage downward through the tube 12 and the medicinal preparation.

I have found by practical experience that my device is very useful and efficacious in administering medicated fumes in the treatment of catarrh, asthma and all bronchial and pulmonary troubles.

Having fully described my invention, what I claim is:

An inhaler, comprising a container having an enlarged bottom portion and a smaller neck portion, a closure having a flange seated in the neck portion, a hollow closure seated in said first mentioned closure and extending therethrough, the bottom end of said hollow closure being closed and the upper end open, a tube inserted through the first mentioned closure and having its lower end located adjacent the bottom of the container, said tube being provided with a goose-neck the lower end of which being located in the upper end of the hollow closure and projecting downwardly therein, a body of medicated air filtering material located in the hollow closure and around the downwardly projecting portion and open end of said goose-neck, and a mouth-piece provided with a flattened end and its opposite end being inserted through the first mentioned closure.

In testimony whereof, I have signed my name to this specification.

EDWARD W. BLACKWOOD.
